SIGNAL AND CONTROL SYSTEM FOR
ELEVATORSWilliam F. Eames, Edgewood, Pa., assignor to
Westinghouse Electric Elevator Company, Chi-
cago, Ill., a corporation of Illinois

Application February 7, 1934, Serial No. 710,104

34 Claims. (Cl. 177—336)

My invention relates to signal and control systems for elevators and more particularly to systems in which the intending passengers may operate push buttons at the floor landings to effect the giving of stop signals in approaching cars and the car attendants may operate control devices in the cars to cause the cars to stop when they arrive at the floors indicated by the stop signals.

One object of my invention is to provide a signal and control system which will promote the answering of calls and the loading and unloading of passengers in a prompt and efficient manner.

Another object is to relieve the car attendants of the necessity of waiting until their cars are within predetermined distances of the floors for which stop signals have been received, before setting the stopping means to cause the cars to stop at the floors indicated by the stop signals upon their arrival thereat.

Another object is to provide for promptly notifying a waiting passenger at a floor which car will stop for him when the attendant on the nearest approaching car conditions its control system to make the stop when it arrives at the floor indicated by the stop signal.

A further object of my invention is to provide a signal and control system in which the conditioning of a car, upon the receipt of a stop signal from a floor, to cause that car to stop at that floor upon its arrival thereat, will prevent any other car from receiving the same stop signal.

A still further object is to provide means, in a system having annunciators in the car to indicate to the car attendant the floors at which stops should be made for waiting passengers, so that when a prospective passenger presses a stop button at a floor, only the annunciator in the nearest car approaching in the desired direction will be operated to indicate that a stop is to be made at that floor.

It is also an object of my invention to provide a signal and control system which requires only one set of push buttons in the car which may be selectively operated to cause the car to stop at any desired floor upon its arrival thereat, either when a passenger desires to get off at that floor or when a stop signal is received from a passenger at that floor.

These and other objects which will appear hereinafter may be attained by means of the apparatus and system hereinafter described and illustrated in the accompanying drawings, wherein:

Figure 1 is a diagrammatic representation of an elevator installation embodying my improved signal and control system;

Fig. 2 is an enlarged representation of the contact segments and cooperating contact brushes on the floor selector of one of the cars shown in Fig. 1;

Figs. 3, 4 and 5, collectively, constitute a diagrammatic representation, in what is known as the straight-line style, of the signal and control system used in operating the elevator cars shown in Fig. 1;

Figs. 3A, 4A and 5A, collectively, constitute an explanatory illustration of the relays embodied in Figs. 3, 4 and 5; and

Fig. 6 represents a key to the conventional forms for the contact members, relay coils, etc., shown in Figs. 3 to 5A inclusive.

The relays illustrated in Figs. 3A, 4A and 5A are shown with their coils and contact members disposed in such positions as to be in horizontal alignment with the positions in the straight line circuits of Figs. 3, 4 and 5, so that the identification of any relay, the number and kind of its contact members and the position of its coil and contact members in the straight line circuits, may be readily determined by an examination of the drawings.

For convenience in reading the drawings, Fig. 4 should be placed under Fig. 3, Fig. 5 under Fig. 4, Fig. 3A beside Fig. 3, Fig. 4A beside Fig. 4 and under Fig. 3A, and Fig. 5A beside Fig. 5 and under Fig. 4A.

Referring more particularly to the drawings, I have illustrated an elevator installation embodying two cars A and B for serving five floors or landings. The cars are indicated as suitably suspended by hoisting cables 11 and 12, which pass over hoisting drums 13 and B13 to suitable counterweights 15 and 16, respectively.

Although I have, for the sake of simplicity, illustrated only two cars and a signal and control system therefor, as applied to only five floors, it is to be understood that the system is equally applicable to any suitable number of cars for serving any suitable number of floors.

For convenience, the main relays in the system are designated as follows:

A=car A.

B=car B.

C=stop push buttons in car A.

CC=holding coils for car buttons in car A. 50

D=down direction switch for car A.

E=inductor relay for decelerating car A.

F=inductor relay for stopping car A.

G=relay for maintaining inductor relays energized for car A. 55

H=relay for restoring or deenergizing inductor relays for car A.

J=stop signal push buttons at floor landings, common to both cars.

5 K=relays for preventing other cars receiving a stop signal after it has been accepted by a car, common to both cars.

L=floor lanterns for car A.

M

N

O

P

Q

10 =response signalling relays for car A.

R=stop signal registering relays, common to 15 both cars.

S=stopping relay for energizing inductor relays to stop car A.

T=stop signal lamps in car A.

U=up direction switch for car A.

20 V=high speed relay for car A.

W=up direction preference relay for car A.

X=down direction preference relay for car A.

Y=zone feeding relays for car A.

Z=zone relays, common to both cars.

25 The relays for car B are given the same reference characters as those given for car A plus the letter "B". The prefix letters U and D indicate "up" or "down" direction. The prefix numerals indicate the floors; the suffix numerals indicate the contact members of the relays. For instance, the reference character B4UY designates an "up" zone feeding relay for the fourth floor for car B, and B4UY1 designates one pair of the contact members of that relay.

30 Referring to the control system for car A as shown in Figs. 2 and 3, the hoisting drum 13 is directly coupled to an armature 17 of a hoisting motor 18, the field winding 19 of which is connected, for constant voltage energization, to a 35 suitable source of electric energy designated by the supply conductors L+1 and L-1. It should be noted that the supply conductors extend through the system shown in Figs. 3, 4 and 5, the additional sections being marked L+3, L-3, L+4, L-4, L+5, L-5, L+6 and L-6.

40 A variable voltage system of control, such as is old and well known in the art, may be provided for operating the hoisting motor 18. In such systems, as shown in Fig. 3, the armature 17 is connected in a loop circuit with the armature 21 of a generator 22. The generator is provided with a separately excited field winding 23 and a cumulative series field winding 24. A 45 resistor R24 is disposed in the circuit of the separately excited field winding 23 for controlling the operation of the generator. The armature 21 of the generator may be driven by a suitable driving motor 25 which may be connected to a suitable source of supply as represented by the conductors and switch 26.

50 A brake 5 is provided for operation by a brake magnet 6 to apply a braking effect to the hoisting drum 13 when the car is stopped, the brake magnet 6 being energized to release the brake 5 55 while the car is running and being deenergized to apply the brake 5 when the supply of power to the car is cut off.

55 The direction and speed of the hoisting motor 18 may be suitably controlled by controlling the direction and the value of excitation current in the separately excited field winding 23. The direction of the excitation current may be suitably controlled by an "up" direction switch U and a "down" direction switch D, and the value of the current may be controlled by means of a

speed relay V, which controls the resistor R24 in the generator field circuit.

The closing of the "up" direction or the "down" direction switches U and D, as well as the high speed control relay V, may be effected by means 5 of an "up" push button UP and a "down" push button DP that are mounted in the car in the position to be actuated by the car attendant.

Any suitable means may be employed for automatically stopping the car A level with the floors 10 it serves. As one example of such means I have illustrated an automatic inductor relay landing system similar to that disclosed in Patent No. 1,884,446, issued October 25, 1932, to K. M. White and G. K. Hearn, assignors to Westinghouse 15 Electric Elevator Company.

The inductor landing system for car A includes a decelerating inductor relay E and a stopping inductor relay F (see Fig. 1) for causing the car to be automatically decelerated from its 20 high speed and brought to a stop at an exact level with the floor. The decelerating inductor relay E is mounted on the car A in position to cooperate with an inductor plate UE for the up direction and an inductor plate DE for the down 25 direction mounted in the hatchway. The stopping inductor relay F is mounted on the car A in position to cooperate with an inductor plate UF for the up direction and an inductor plate DF for the down direction. For simplicity, only 30 one set of inductor plates for one floor has been shown, but it will be understood that a set similar to that shown is to be provided for each floor served by the car intermediate the upper terminal landing and the lower terminal landing. At the terminal landings, a set of inductor plates corresponding to the inductor plates UE and UF may be provided for the upper terminal and a set corresponding to inductor plates DE and DF may be provided for the lower terminal. 35

40 As shown, each inductor relay is provided with two sets of contact members. For an "up" stop, the contact members E1 of relay E cooperate with the inductor plate UE in decelerating the car, and the contact members F1 of relay F 45 cooperate with the inductor plate UF in stopping the car after it has decelerated. For the "down" direction the contact members E2 of relay E cooperate with the inductor plate DE to decelerate the car A and the contact members F2 cooperate 50 with the inductor plate DF in stopping the car.

The inductor relays are of the self-holding type, that is, when they are energized but have not yet come opposite an inductor plate, the contact members remain closed, but when the 55 relay comes opposite an inductor plate, the contact members adjacent that plate move to an open position and are held in such open position until the inductor relay is deenergized. The means for holding the contact members in the 60 open position on inductor relay E, for instance, are the extended portions 28 and 29 (Fig. 1).

65 For instance, it will be seen that when the inductor relay E passes the down inductor plate DE in an energized condition, the contact members E2 will be opened, and the arm 29a will be moved upwardly to such a position that they would be attracted and held by the magnetized projection 29. Therefore, the opened contact members remain open and do not reclose after 70 passing the inductor plate to complicate the operation of the control system. However, I do not desire to be limited to inductor relays of this particular type because inductor relays with temporary opening contact members which are well 75

known in the art may be employed just as readily if the motor control system is adjusted to cooperate with them.

The contact members on the inductor relays just described are so connected with the car control circuits that, when the inductor relays are energized to decelerate and stop the car at the floor represented by the inductor plates in the "down" direction, the contact members **E2** pass the inductor plate **DE** and are thereby opened to decelerate the car, by deenergizing the speed relay **V**, and as the contact members **F2** come opposite the inductor plate **DF**, they open to stop the car level with the floor by opening the "down" direction switch and applying the brake **5**. The contact members **E1** of relay **E** and the contact members **F1** of the relay **F** are opened by the inductor plates **UE** and **UF**, respectively, when a stop is made in the "up" direction. When the inductor relays are energized to stop the car, it is desired to maintain them in that condition until they are operated by passing the inductor plates to bring the car to rest. A slow-down holding relay **G** is provided for this purpose, (see Fig. 3).

When the inductor relays are energized to effect a stop, the relay **G** holds them energized until they are restored, even though their contact members are operated to open as the relays pass the inductor plates. Therefore, an inductor restoring relay **H** is provided for deenergizing the inductor relays of car **A** after a stop has been made and also for so interlocking them that they may be energized only when the car is moving.

The exact position of the inductor plates in the hatchway and of the inductor relays on the cars cannot be here given because the position of these devices varies in each installation by reason of differences in hoisting motors, weight of cars, height of ceilings, etc. However, in the many commercial installations of inductor stopping systems already made, it has been found that the mechanics have no difficulty in ascertaining the precise positions in which the plates and relays should be placed when the cars are first tried out in operation.

In the elevator system illustrated in the drawings, the energization of the inductor relays on car **A** for decelerating and stopping the car at a floor is effected by a stopping relay **S**. This relay is energized, as the car nears the floor at which a stop is to be made and, in turn, energizes the inductor relays on that car so that they will, as they pass the inductor plates for that direction for that floor, cause the car to decelerate and stop at the floor.

The stopping relay **S** is controlled by a plurality of "stop" push-buttons (one for each floor) in the car **A**; so that the pressing of a car button by a car attendant at any time will at once register a stop call which will later cause the stopping relay **S** to be energized to stop the car at the floor corresponding to that push button. By "registering" a stop call, I mean the act of initiating and maintaining a circuit which will be completed later as the car nears the floor corresponding to the operated button and thereby then energize the stopping relay **S** to energize the inductor relays to stop the car at that floor. With this system, the car attendant may stop the car at any floor by pressing the corresponding push button in the car, either to let off passengers or to take on passengers.

The "stop" push buttons in car **A** are desig-

nated as **1C**, **2C**, **3C**, **4C** and **5C** for the first, second, third, fourth and fifth floors, respectively.

Associated with the respective car push buttons for car **A** are holding or registering coils **1CC**, **2CC**, **3CC** and **5CC**. These coils operate to hold the car push-buttons in a depressed position after they are pressed by the car attendant to cause the car to stop at selected floors. The coils are automatically deenergized when the car reaches the terminal floors to release the buttons for the next direction of operation.

Inasmuch as stop push buttons have been disposed in the cars to enable the car attendants to stop the cars at the various floors, it is desirable to have some means whereby waiting passengers at the various floors may give stop signals to the attendants in the cars. Therefore, each car is provided with an annunciator to be operated by push button switches disposed at the floor landings in position to be operated by the waiting passengers at the landings. The annunciator in car **A** is designated by the numeral **27**; that in car **B** by the numeral **B27**.

The floor push-button switches are designated as **1UJ**, **2UJ**, **3UJ**, and **4UJ** for the up direction at the first, second, third and fourth floors, and as **5DJ**, **4DJ**, **3DJ**, and **2DJ** for the down direction at the fifth, fourth, third and second floors.

The floor button switches are common to both cars; that is, there is only one button for each direction at each floor, regardless of the number of cars, and a waiting passenger needs to press only one button for the direction in which he desires to go in order to set up a stop signal in the nearest approaching car for that direction.

The annunciators in the cars may be of any suitable kind. The one shown in car **A** is provided with a plurality of small signal devices such as electric lamps for indicating the floors at which stops should be made to take on waiting passengers, there being one lamp for each direction for each of the intermediate floors and an up lamp for the lower terminal and a down lamp for the upper terminal. The signal lamps in the annunciator **27** in car **A** are designated as **1UT**, **2UT**, **3UT** and **4UT**, corresponding to the first, second, third and fourth floors in the up direction, and as **5DT**, **4DT**, **3DT** and **2DT**, corresponding to the fifth, fourth, third and second floors in the down direction. The lamps for each floor are placed behind a single jewel. For instance, the lamps **4UT** and **4DT** for the fourth floor are placed behind the jewel **27a** for the fourth floor, so that the lighting of either lamp will illuminate the jewel. When the jewel is illuminated on an up trip, the operator knows that he is being signalled to make an up stop at the fourth floor. On the other hand, when the jewel is illuminated on a down trip, the operator is being signalled for a down stop.

Associated with the floor push buttons are registering relays **1UR**, **2UR**, **3UR** and **4UR** for the "up" direction and **5DR**, **4DR**, **3DR** and **2DR** for the "down" direction. These relays operate to maintain a floor button circuit in its completed condition after its button is pressed until the stop signal is accepted by a car; that is, until a car attendant acknowledges the stop signal by pressing the stop button in his car for the corresponding floor to cause that car to stop when it arrives at that floor.

With this system, the temporary operation of a floor button will register or, in other words, initiate and maintain a circuit which will light

the corresponding stop signal lamp in the annunciator of the nearest approaching car for that floor and in the direction corresponding to the operated button and it will not be necessary to 5 continue pressing the button after it is once operated to maintain the stop signal in the car. Also by reason of this system the signal lamp in the annunciator of the nearest approaching car in the desired direction will light as soon as the 10 button is pressed.

When a waiting passenger at a floor presses a push button at that floor, thus lighting the stop signal lamp in the next car for that floor, and the attendant in that car, upon observing the 15 lighted stop signal, presses the corresponding car button to cause the car to stop when it arrives at the floor where the passenger is waiting, it is desirable to have some means for informing the waiting passenger that the car attendant has 20 recognized his stop signal and will make a stop for him. It is also desirable to indicate which car will make the stop so that the passenger may at once walk to the hatchway, door for that car and be prepared to enter the car as soon as it arrives 25 and the doors open. To accomplish this purpose, I have provided a plurality of signal or indicating devices, preferably electric lamps, which are mounted outside of the elevator shafts at the floor landings. These lamps are usually known 30 as floor lanterns.

Each of the top and bottom floors is provided with a single floor lantern for each car, the lanterns at the lower floor terminal to indicate the "up" direction and the lanterns at the upper 35 floor or terminal to indicate the "down" direction. Each of the intermediate floors is provided with a pair of lanterns for each car, one lantern to indicate that the corresponding car is approaching for the "down" direction and will make 40 a "down" stop at the floor, and the other lantern for indicating that the car is approaching the floor for an "up" direction and will make an "up" stop. The responsive signal is given immediately upon the pressing of the car button by 45 the car attendant, even though the car may be many floors away from the floor where the stop signal originated.

The floor lanterns for car A (Fig. 3) are designated as 1UL, 2UL, 3UL and 4UL for the "up" 50 direction at the first, second, third and fourth floors, and 5DL, 4DL, 3DL and 2DL for the fifth, fourth, third and second floors in the "down" direction.

In order to provide for the immediate illumination of the floor lanterns in response to the 55 operation of the car button by the car attendant, so that the waiting passenger may step to the door indicated and be ready to board the car when it arrives, I have provided a plurality of response signalling relays which are individual to the cars and which are operated by the stop push buttons in the cars. The response signalling relays for car A are designated as M, N, O, P and Q.

It may be noted here that the registering relays 60 1UR, 2UR, etc., also have contact members in the circuits of the response signalling relays to prevent their operation and consequently the operation of a signal light at a floor when a car button is operated to stop a car if the push button 65 at that floor has not been operated by a waiting passenger. If this function were not provided, a plurality of cars might have their car buttons operated to stop them at a floor where a waiting passenger had pressed a button and 70 the floor lanterns for all cars would be lighted,

thus confusing the waiting passenger as to which car would be first to arrive and stop for him.

Each of the response signalling relays is provided with a cancellation coil which may be energized to restore the response signalling relays to 5 their normal condition after they have been operated. The cancellation coils for the response signalling relays for car A are designated as MC, NC, OC, PC and QC.

When a waiting passenger at a floor presses 10 the push button to give a stop signal to an approaching car, it is desirable to have the stop signal given on the annunciator in the nearest approaching car for the desired direction but not affect the annunciators in the other cars. It is 15 also desirable to so operate the response signalling relays that the car attendant may operate the stop buttons in the car, immediately upon receipt of a stop signal, to cause the car to make the desired stop, without waiting until the car 20 gets within a predetermined distance of the floor at which the stop is to be made. That is, the car attendant may set the car for a stop and the system will automatically take care of making the stop when the car arrives at the floor at 25 which the stop is to be made.

In order to accomplish these purposes, I have provided a plurality of zone relays and zone feeding relays. The zone relays (Fig. 4) are common to both cars, are operated by the zone feeding 30 relays and are designated as 2UZ, 3UZ and 4UZ for the up direction and 4DZ, 3DZ and 2DZ for the down direction. The zone feeding relays are individual to each car and are operated in accordance with the position of the car, those for 35 car A being designated as 1UY, 2UY, 3UY and 4UY for the up direction for the first, second, third and fourth floors and as 5DY, 4DY, 3DY and 2DY for the down direction at the fifth, fourth, third and second floors. 40

The zone relays divide the "up" signal circuits and also the "down" signal circuits of the cars into a plurality of sections. For instance, the signal circuits represented by the conductors 43 and 44 leading to the stop signal lamps 1UT, etc., 45 in car A (see Fig. 3) are divided into sections by the contact members 2UZ1, 2DZ1, etc., of the zone relays.

The zone feeding relays control the zone relays and other contact members in such manner as 50 to so connect the circuit sections that the shaft travel of all the cars is divided into as many effective "up" signal circuit zones as there are cars on the "up" trip and into as many effective "down" signal circuit zones as there are cars on 55 the "down" trip.

The zone feeding relays, being operated in accordance with the positions of the cars, also assign the circuit zones to the several cars; that is, they assign one zone to each car. The effective circuit zone assigned to any one car is that portion of the circuit in advance of that car up to the next car ahead of it. The effective zone for each car is elastic and keeps moving along with that car and the next car in front thereof, 65 the length of the zone for any car being determined by the position of that car and the position of the next car ahead of it.

The zone feeding relays not only assign the zones to the cars but they also feed such zones 70 after they are assigned; that is, they connect the assigned zones to a supply circuit in such manner as to prepare the relays, etc., in the zone circuit for energization.

After the attendant in the car acknowledges 75

5 a stop signal given by a waiting passenger at a floor; that is, after he has pressed the corresponding car button to stop his car in response to the stop signal when the car arrives at the floor, it is desirable to have some means for preventing any of the other cars in the system from receiving the same stop signal. I have provided such a means in the form of a plurality of preventing relays designated as 1UK, 2UK, 3UK and 10 4UK for the "up" direction for the first, second, third and fourth floors, and 5DK, 4DK, 3DK, and 2DK for the "down" direction for the fifth, fourth, third and second floors. The preventing relays are common to both cars and are operated 15 by the response signalling relays that are individual to each car.

20 In order that certain circuits may be conditioned for operation only when car A is moving upwardly and other circuits may be conditioned for operation only when car A is moving downwardly, I have provided an "up" direction preference relay W and a "down" direction preference relay X, which relays operate in accordance with the direction in which the car is operated.

25 25 In order that the various circuits for the push buttons, floor lanterns, relays, etc., may be connected in accordance with the position of the cars with respect to the floors past which they operate, the car A is provided with a floor selector SE and the car B with a floor selector BSE. The floor selectors may be of any suitable type such as are usually employed in elevator systems, and may be located at any suitable point such for example as in the penthouse or in the elevator 30 shafts.

30 35 The floor selector SE for car A is provided with a set of "up" contact segments and a set of "down" contact segments (Fig. 2) which are arranged according to the floors and which are disposed to be engaged by cooperating brushes 30 to 37, inclusive, mounted upon and insulated from a movable arm SM.

35 40 The movable arm SM is operated in accordance with the movements of car A by means of a screw shaft 38 that may be driven by some part of the operating mechanism of the car. A frictional engagement between the arm SM and its operating screw 38 will cause the arm to bear upon the "up" contact segments when the car is traveling upwardly and upon the "down" contact segments when the car is traveling downwardly. It will be understood that the arm will tilt from one side to the other when the direction of operation of the car is reversed.

45 50 However, in the present system, when the car is at a terminal, it is desirable to have the arm SM tilt to the opposite direction as soon as the car is conditioned to travel in the opposite direction without waiting until the car actually begins to move. For this purpose each floor selector is provided with a pair of electromagnets which tilt the floor selector arm for the "up" direction when the car is at the lower terminal upon the car's "up" switch being closed, and to tilt the 55 selector arm to the "down" direction when the car is at the upper terminal upon the car's "down" switch being closed. The electromagnets on the floor selector SE (Fig. 1) for car A are designated as 40 for the "up" direction and 70 41 for the "down" direction.

55 60 The group of "up" contact segments designated as a under the brush 30 (Fig. 2) are energized when stop calls are registered on the car stop buttons for the purpose of energizing the stopping relay S to stop the car on its "up" trip when

it approaches a floor at which an "up" stop is to be made.

65 The group of "up" contact segments designated as b under the brush 31 completes the circuits for cancelling or restoring the response signalling relays when a stop is completed.

70 The group of "up" contact segments c under the brush 32 are energized by the response signalling relays to cause the lighting of the floor lanterns when the car is to stop at the floors 10 for which car stop buttons have been operated.

75 The "up" contact segments designated as d under the brush 33 serve to so connect the circuits to the zone feeding relays that these relays will be energized in accordance with the position 15 of the car.

80 The contact segments on the "down" side of the floor selector are engaged by the "down" brushes 34, 35, 36 and 37 when the car is descending and correspond to the contact segments just described for the "up" direction, those marked e being the stopping segments, f the cancellation segments, g the down floor lantern segments, and h the "down" zone relay feeding 25 segments.

85 The floor selector BSE for car B is similar to the one described for car A and inasmuch as the control system for car B is similar to that just described for car A, a detailed description of the control system for car B will be omitted.

90 95 It may be noted here that the spacing and positioning of the contact segments on floor selectors is an old art, and that the position of the segments cannot be selected until the height of a building, the distances between floors, etc. for a given installation are known. After these details are supplied, any mechanic acquainted with the art will be able to produce a satisfactory selector to connect the circuits of the cars in accordance with the floors past which they 40 operate.

100 The invention may be understood best from an assumed operation of the apparatus illustrated in the drawings.

105 The switch 26 (Fig. 3) and the switch B26 (Fig. 5) are closed to start the motor generator sets of the cars. The switches 20 (Fig. 3) are closed to prepare the control systems of both cars for operation.

110 115 The closing of the switches 20 connects the supply conductors L1 to L6 inclusive to a suitable source of energy (not shown), thereby energizing the field winding 19 of the hoisting motor 18 of car A and the field winding B19 of the hoisting motor B18 of car B to prepare them 55 for operation.

120 125 It will be assumed that car A is standing at the lower floor with its door open and that car B is standing at the third floor with its door open on a down trip.

130 135 Inasmuch as car B is standing at the third floor on a down trip its down direction preference relay BX is energized by a circuit extending from the supply conductor L+5 (Fig. 5) through the contact members BUP2, the coil of relay BX and the contact members BW5 to the supply conductor L-5. The down electromagnet B41 is in parallel with the coil BX and is, therefore, also energized for tilting the arm BSM to the down 140 side of the floor selector BSE, causing its down brushes to engage the down contact segments on the floor selector. The energization of the down direction preference relay BX also connects various circuits for the down operation of car B.

145 150 Inasmuch as car B is standing at the third floor

on a down trip, the floor lantern B3DL at the third floor is lighted by a circuit extending from the supply conductor L+6 through the lamp B3DL, the contact segment B3g, brush B3e and the contact members BH2 to the supply conductor L-6. The down lamp B3DL for car B will remain lighted while car B stands at the third floor.

In this position of car B the zone feeding relay brush B3f for car B is in engagement with the down contact segment B3h, thereby energizing the zone feeding relay B3DY to close its contact members B3DY1, B3DY2 and B3DY3. The closing of the contact members B3DY1 energizes the zone relay 3DZ to cut off the signal circuits behind car B. Hence that zone in the circuit for car B behind car B is an ineffective zone for car B. This is done by the opening of the contact members 3DZ4 (Fig. 5) and the opening of the contact members 3DZ2 (Fig. 3) in the circuits leading to the responsive signalling relays M, N and O and by opening the contact members 3DZ1 in the circuit leading to the stop signal lamp 3DT in car A, and by opening the contact members 3DZ3 (Fig. 5) leading to the signal lamp B3DT in car B. The closing of the contact members B3DY2 of the energizing zone-feeding relay B3DY connects the signal circuit zone ahead of car B to the supply conductor L-6 so that the operation of a down floor button at a floor ahead of car B will light the stop signal. Hence that zone in the circuit for car B ahead of car B is an effective zone for car B.

The closing of the contact members B3DY3 connects the signal zone circuit of the response signalling relays BP and BQ to the supply conductor L-5 so that the attendant in car B can acknowledge all stop signals received by him and cause the lighting of the floor lanterns for car B at the floors where stop signals for car B have originated.

Turning now to a consideration of car A standing with its door open at the lower floor, it will be assumed that the car attendant presses the up direction push button UP to prepare the car for an up trip. However, the car will not start upwardly because the door is open and the open door contact members 50 prevent the control circuit from operating the motor to move the car upwardly. It is to be understood that any one of the old and well known switch systems may be employed for starting the car and that the present push button system is illustrated merely for the sake of simplicity.

The closing of the contact members UP1 of the up direction push button UP prepares a circuit for energizing the up direction relay U, which circuit will be completed when the doors are closed.

The operation of the up push button UP (Fig. 3) opens its contact members UP2 thereby deenergizing the down direction preference relay X, which, in turn, closes its contact members XI1, thereby completing a circuit for energizing the up direction preference relay W to prepare the circuits of car A for the up trip. The circuit for relay W extends from the supply conductor L+1 through the contact members DP2, the coil of relay W and the contact members XI to the supply conductor L-1.

Inasmuch as the down direction preference relay X has been deenergized to open its contact members X3 and the up direction preference relay W has been energized to close its contact members W3, the holding coils 1CC, 2CC, 3CC, 4CC and 5CC for the car buttons in car A have

been deenergized to release all the push buttons operated on the down trip and have been reenergized so that on the up trip as a car push button is pressed inwardly, it will be held in that position by the corresponding holding coil until the car gets to the end of its up trip.

The coil of the electromagnet 40 which is in parallel relation to the coil of the relay W is also energized by the closing of the contact members XI of relay X to tilt over the floor selector arm 10 SM, thereby prepared the floor selector of car A for the up trip.

With the floor selector arm in the up position, the brush 32 engages the contact segment 1c and thereby completes a circuit for lighting the up 15 floor lantern 1UL at the lower floor, which circuit extends from the supply conductor L+2 through the up lamp 1UL, the contact segment 1c, brush 32 and the contact members H2 to the supply conductor L-2, the contact members H2 being closed because the restoring relay H is deenergized on account of the car standing at the floor. Thus it is seen that the standing of a car at a floor will cause the lighting of the floor lantern 20 at that floor for that car.

The contact brush 33 also engages the contact segment 1d, thereby energizing the zone feed relay 1UY by a circuit extending from the supply conductor L+2 through the coil 1UY, contact segment 1d and brush 33 to the supply conductor 30 L-2.

The closing of the contact members 1UY1 feeds the zone circuit represented by conductor 43 leading to the up lamps 2UT, etc. in the announcer 35 27 in car A, that is, these contact members connect one side of the zone circuit 43 to the supply conductor L-2.

The closing of the contact members 1UY2 feeds the zone circuit represented by the conductor 46 leading to the response signalling relays 40 P, O, M, and N for car A; that is, it prepares these relays for operation when the car buttons are operated.

It will be assumed now that a waiting passenger at the third floor desirous of travelling up- 45 wardly, presses the "up" stop signal push button 3UJ at the third floor, in order to give a stop signal to the nearest approaching car in the up direction.

It will also be assumed that a down passenger 50 waiting at the fourth floor presses the down button 4DJ to cause the giving of a stop signal for the fourth floor in the nearest approaching down car.

The pressing of the down push button 4DJ at 55 the fourth floor energizes the stop call registering relay 4DR by a circuit extending from the supply conductor L+3 through the down button 4DJ, the coil of relay 4DR and the contact members 4DK2 to the supply conductor L-3. The energization of the relay 4DR closes its contact members 4DR3, thereby establishing a holding circuit around the push button 4DJ and causing the registering relay 4DR to remain energized until the contact members 4DK2 are opened. In other 60 words, the down stop call at the fourth floor is now registered and will remain registered until a car answers it. Inasmuch as no car is above the down stop at the fourth floor, no circuit can be completed as yet for giving a down stop signal 65 in a down car for the fourth floor.

The pressing of the push button 3UJ energizes the stop call registering relay 3UR by a circuit extending from the supply conductor L+3 (Fig. 4) through the contact members of button 3UJ 75

the coil of relay 3UR and the contact members 3UK2 to the supply conductor L-3.

The energization of this relay causes the up stop signal for the third floor to be registered or in other words stored up until it is finally answered by some car, regardless of the fact that the waiting passenger does not keep his finger on the push button 3UJ all the time.

The energization of the relay 3UR closes its contact members 3UR1, 3UR2, 3UR3, 3UR4 and 3UR5. The closing of the contact members 3UR3 completes a holding circuit around the push button 3UJ whereby the registering relay 3UR is maintained in energized condition until the contact members 3UK2 are opened.

The closing of the contact members 3UR1 completes a circuit for lighting the stop signal lamp 3UT in car A, to indicate to the attendant in that car that he should stop at the third floor on his up trip. This circuit extends from the supply conductor L+2 to lamp 3UT, contact members 3UR1 and 3UK1 to circuit 43 and thence through contact members 2UZ1 and 1UY1 to the supply conductor L-2.

It will be assumed now that the attendant in car A notices the lighting of the up lamp 3UT, indicating an up stop at the third floor and presses the car button 3C in response to the stop signal. The operation of the button 3C lights an up signal lantern for car A at the third floor to indicate to the waiting passenger that car A will make a stop for him; it prepares to automatically stop the car when it arrives at the third floor and it prevents any other car from picking up or accepting the "up" stop signal for the third floor.

The pressing of the car button 3C causes it to be held "in" by the energized holding coil 3CC. In this pressed position, the closed contact members of the button 3C energize the stopping contact segment 3a for the third floor and also complete a circuit for energizing the response signalling relay O, which circuit extends from the supply conductor L+1 (Fig. 3) through the contact members of push button 3C, the coil of response signalling relay O, conductors 47 and 48, contact members W6 and 3UR2 to the signal circuit 46 and the contact members 2UZ2 and 1UY2 to the supply conductor L-1.

The energization of the response signalling relay O causes it to close its contact members O3 (adjacent the coil O) thereby completing a self-holding circuit for itself and causing it to remain energized until the restoring coil OC is energized to restore it to its normal condition.

The closing of the contact members O1 of relay O completes a circuit for lighting the up floor lantern 3UL for car A at the third floor, which circuit extends from the supply conductor L+2 through lamp 3UL and contact members O1, conductor 49 and contact members W2 to the supply conductor L-2. Thus, it is seen that the floor lantern at the third floor for car A is lighted as soon as the car attendant presses the corresponding stop car button and thereby indicates to the waiting "up" passenger at the third floor that his call has been acknowledged, that a car will stop for him and which door the car will stop at so that he may at once step to that door and be ready to board the car when it arrives and the door opens.

The energizing of the relay O also closes its contact members O4, thereby energizing the preventing relay 3UK by a circuit extending from the supply conductor L-3 (Fig. 4) through the

contact members O4 and W10 and the coil 3UK to the supply conductor L-3. The energization of relay 3UK operates to prevent any other car from receiving the up stop signal registered for the third floor and accepted by car A. To do this, the energized relay 3UK opens its contact members 3UK3 (Fig. 5) in the circuit leading to the up signal lamp B3UT in the annunciator B27 of car B. Thus it will be seen that even though car B should pass car A on the way to the third floor, the "up" stop signal lamp for the third floor cannot be lighted in car B.

The energization of relay 3UK also opens its contact members 3UK1 (Fig. 3) in the circuit to the "up" stop signal lamp 3UT in car A, thereby extinguishing that lamp.

The energization of the relay 3UK also opens its contact members 3UK2, thereby deenergizing the registering relay 3UR and restoring it to its normal condition. However, relay 3UR cannot be reenergized until the call is answered, because the contact members 3UK2 will remain open until the call is answered.

It will be assumed now that the car attendant starts the car to make an up trip by closing the car door (not shown). Inasmuch as the car attendant has already closed the up switch UP, the closing of the car door and, therefore, the door and gate contact members 50 completes a circuit for energizing the up direction switch U to move the car upwardly. This circuit extends from the supply conductor L+1 (Fig. 3) through the contact members UP1 of push button switch UP, the coil of up direction switch U, the contact members D5 and F2 and the door contact members 50 to the supply conductor L-1. The energization of the up direction switch U closes its contact members U1, U2, U3, U5 and U6 and opens its contact members U4, to effect the upward movement of the car.

The closing of the contact members U5 completes a self-holding circuit around the contact members UP1 of button UP for the coil of up direction switch U, thereby maintaining that switch in an energized condition until the stopping inductor relay opens its contact members F2.

The closing of the contact members U1 and U2 energizes the separately excited field winding 23 of the generator 22, by a circuit extending from the supply conductor L+1 through the contact members U1, the separately excited field winding 23, the contact members U2 and resistor R24 to the supply conductor L-1.

The closing of the contact members U3 completes a circuit for energizing the brake magnet 6 to release the brake 5 by a circuit extending from the supply conductor L+1 through the contact members U3 and the coil of electromagnet 6 to the supply conductor L-1. The closing of the contact members U3 also completes a circuit through the restoring relay H which is in parallel with the brake magnet 6.

The restoring relay H upon being energized closes its contact members H1, thereby preparing the circuits of the decelerating and stopping inductor relays E and F for energization when a stop is to be made.

The opening of the contact members H2 of relay H extinguishes the up lamp 1UL at the first floor.

The opening of the contact members U4 of the up switch U interlocks the circuit for the down direction switch and prevents energization of

75

that switch while car A is being operated upwardly.

Inasmuch as the field winding 23 is energized and the brake 5 is released by the energization of the brake magnet 6, the generator 22 supplies current to the hoisting motor 18 which, in turn, operates the hoisting drum 13 to raise the car in the hatchway (not shown). The energization of the up direction switch U also closes its contact members U6, thereby energizing the high speed relay V by a circuit extending from the supply conductor L+1 through the contact members U6 and E1 and the coil V to the supply conductor L-1.

15 The energization of the high speed relay V closes its contact members V1 to eliminate the resistor R24 from the circuit of the field winding 23 of the generator 22, thereby causing the variable voltage system to operate the car at high speed.

20 The car now starts upwardly and in so doing causes the floor selector arm SM to move upwardly on the floor selector, thereby moving the brush 30 up along the row of contact segments 25 a. As car A comes within a suitable predetermined distance of the third floor, the brush 30 engages the contact segment 3a energized by the car button 3C and thereby completes a circuit for energizing the stopping relay S, which circuit extends from the supply conductor L+1 through the contact members of push button 3C, the contact segment 3a, brush 30, conductor 51 and the coil of relay S to the supply conductor L-1. The energized stopping relay S closes its contact members S1, thereby completing a circuit for energizing the decelerating inductor relay E to decelerate the car as it moves closer to the third floor. The circuit for this relay extends from the supply conductor L+1 through the coil E and thence through the contact members S1 and H1 to the supply conductor L-1.

25 Inasmuch as the inductor maintaining relay G is in parallel with the coils E and F, it is also energized by the closing of the contact members S1 and thereupon closes its contact members G1 to provide a self-holding circuit for the inductor relays E and F until the car is stopped and the contact members H1 opened as a result thereof.

30 As the car approaches closer to the third floor the energized inductor relay E passes the "up" high speed inductor plate UE for the third floor and is thereby caused to open its contact members E1, thus deenergizing the high speed relay V which, in turn, opens its contact members V1 and thereby reinsets the resistor R24 in the circuit of the generator field winding 23 to decelerate the car from its high speed to its stopping speed.

35 The deenergization of the high speed relay V also closes its contact members V2 thereby energizing the stopping inductor relay F. The stopping inductor relay F is now energized and will be operated to bring the car to a stop at the third floor as soon as it comes opposite the inductor plate UF.

40 At this time the brush 30 runs off the energized stopping contact segment 3a (Fig. 2) and thereby deenergizes the stopping relay S and restores it to its normal condition.

45 As car A approaches still more closely to the third floor at its stopping speed, the inductor relay F comes opposite the inductor plate UF for 50 the third floor and is thereby operated to open

its contact members F2, thus deenergizing the up direction switch U.

55 The deenergization of the up direction switch U opens its contact members U1 and U2 to deenergize the generator field 23; and opens its contact members U3 to deenergize the brake magnet 6 and the inductor restoring relay H.

60 The deenergization of the field winding 23 and the application of the brake 5 by the deenergization of the brake magnet 6 causes the car to stop level with the third floor; and the deenergization of the relay H opens its contact members H1 to deenergize and restore the inductor locking relay G, the decelerating inductor relay F and the stopping inductor relay E so that they will not be effective to stop the car in its future operation until the stopping relay S is again energized to effect the stopping of the car.

65 The deenergization of the relay H also closes its contact members H3 and thereby completes a circuit for energizing the restoring coil OC on the relay O to return that relay to its normal condition. This circuit extends from the supply conductor L+1 through the contact members H3, brush 31 now on contact segment 3b, contact segment 3f to the coil OC, conductor 47, contact members O3, and conductors 52 and 53 to the supply conductor L-1.

70 The deenergization of the response signalling relay O opens its contact members O4, thereby deenergizing the preventing relay 3UK and returning it to its normal condition, in which condition it closes its contact members 3UK1 to restore the circuit of the "up" stop signal lamp 3UT in car A and closes its contact members 3UK3 (Fig. 5) to restore the circuit for the "up" stop signal lamp B3UT in car B. The restored stop signal lamps are again ready for operation in their proper order under normal conditions. The contact members 3UK2 also close to render the registering relay 3UR effective for the registration of stop calls.

75 Inasmuch as car A is now stopped at the third floor, the car attendant may open the door, permit the waiting passenger to enter and then re-close the door.

80 By the above operation, it is seen that the pressing of a floor call button immediately gives a stop signal in only the nearest approaching car; that the attendant in that car may "set" the car stop button at once upon getting the stop signal regardless of how far away the car is from the floor at which the stop signal originates; that the operation or setting of the car button corresponding to the signalled floor will immediately acknowledge receipt of the stop signal by lighting the floor lantern of that car at that floor, will cancel the registered stop signal and extinguish the stop signal light in the car and maintain such cancellation and extinguishment until the car answers the call, will stop the car when it arrives at the floor and will also prevent any other car from picking up the stop signal or accepting it. By the term "nearest approaching car", I mean the nearest car which is in position or will be in position to make a stop at the floor for the direction of the stop signal after receiving and accepting that stop signal.

85 It will be assumed that the car attendant then operates the up push button UP to start the car upwardly. This operation energizes the up direction switch U, which, in turn, energizes the generator field winding 23, the brake magnet 6, the inductor restoring relay H and the high speed

relay V in the same manner as when the car was moved upwardly from the first floor.

The energization of the inductor restoring relay H opens its contact members H2, thereby opening the circuit to the up lantern 3UL for car A at the third floor, thus extinguishing that lantern. Car A is now moving upwardly toward the upper terminal and it is to be understood that it may be stopped at the upper terminal by a system embodying the old and well known terminal limit switches or by any other suitable means. For convenience in the present system, I have applied the car button stopping system to the terminal floors as well as the other floors. Hence, as car A moves upwardly, the car attendant presses the car button 5C to cause the car to slow down and stop at the fifth floor. The pressing of the button 5C causes it to close its contact members and remain "in" by reason of the energized condition of the holding coil 5CC. The closing of the contact members of the button 5C energizes the stopping segment 5a, but inasmuch as the floor push buttons at the fifth floor have not been operated, the contact members 5DR2 of the registering relay 5DR are open in the circuit to the response signalling relay M and, therefore, relay M is not energized by the pressing of the push button 5C.

Inasmuch as the response signalling relay M is not energized, the floor lantern 5DL at the fifth floor for car A is not lighted.

It will be assumed, however, that after the car attendant presses the car button 5C in car A to stop the car at the fifth floor, a waiting passenger at the fifth floor, not knowing that the car button had been pressed to stop the car at that floor, presses the push button 5DJ at the fifth floor landing.

The pressing of the button 5DJ closes its contact members, thereby energizing the stop call registering relay 5DR by a circuit extending from the supply conductor L+3 (Fig. 4) through the contact members of push button 5DJ, the coil 5DR and the contact members 5DK2 to the supply conductor L-3. The energization of the relay 5DR closes its contact members 5DR3, thus providing a self-holding circuit for itself around the contact members of the push button 5DJ. The stop call at the fifth floor is now registered; that is, it will be held until it is answered by a car.

The closing of the contact members 5DR2 of the energized relay 5DR energized the response signal relay M by a circuit extending from the supply conductor L+1 through the floor button 5C, the coil M, the contact members W4, 5DR2 and 4UY2 to the supply conductor L-1.

It should be understood that the response signal relay M is energized as soon as the floor button 5DJ is pressed, because of the already existing registered stop call on the car button 5C which closed the contact members of the push button 5C leaving the only gap in the circuit for the relay M to be closed by the contact members 5DR2 of the stop call registering relay for the floor button at the fifth floor.

The energized relay M closes its contact members M1 thereby lighting the floor lantern 5DL at the fifth floor for car A to indicate to the waiting passenger which car will stop for him so that he may at once step to the door of that car and be ready to enter it when it arrives and opens the door for him.

The energized response signalling relay M closes its contact members M3, thereby energiz-

ing the preventing relay 5DK (Fig. 4) by a circuit extending from the supply conductor L+3 through the contact members M3 and W8 and the coil 5DK to the supply conductor L-3.

The energization of the preventing relay 5DK opens its contact members 5DK2, thereby deenergizing the registering relay 5DR. Although the registering relay 5DR is restored to its de-energized condition, it cannot be reenergized by pressing the button 5DJ at this time because the contact members 5DK2 are still open and prevent the completion of the energizing circuit for relay 5DR. The registering relay will remain in this condition until the car stops at the floor.

The energized preventing relay 5DK opens its contact members 5DK1 (Fig. 3) in the circuit of the stop signal lamp 5DT in car A to extinguish that lamp and prevent its re-operation for the fifth floor.

The energized preventing relay 5DK also opens its contact members 5DK3 (Fig. 5) in the circuit leading to the stop signal lamp B5DT to prevent car B from picking up the stop signal for the fifth floor if it should pass car A.

From the above, it is seen that the pressing of the floor button after the nearest car approaching for that direction for that floor has already registered a car button stop call for that floor, gives an immediate response signal to the waiting passenger indicating which car will stop.

It is also seen that the attendant in the car uses the same car button to stop the car at a floor regardless of whether the stop call comes from a passenger in the car or from a passenger at the floor.

As car A continues toward the fifth floor, the stopping brush 30 engages the energized stopping segment 5a, thereby energizing the stopping relay S through a circuit extending from the supply conductor L+1 through the contact members of car button 5C, contact segment 5a, brush 30, conductor 51 and the stopping relay S to the supply conductor L-1.

The energization of the stopping relay S opens its contact members S1 to cause the energization of the inductor relays and subsequent operation by the inductor plates for the fifth floor and stopping of the car at the fifth floor in the same manner as has been described in stopping the car at the third floor.

As the car arrives at the fifth floor, the cancellation brush 31 engages the cancelling contact segment 5b, thereby completing a circuit for energizing the restoring coil MC of the response signal relay M, which circuit extends from the supply conductor L+1 through the contact members H3, brush 31, contact segment 5b, contact segment 5f, restoring coil MC, the contact members M2 and conductor 53 to the supply conductor L-1.

The energization of the coil MC deenergizes the coil M and restores it to its normal condition. The deenergization of the relay M opens its contact members M3 in the circuit of the preventing relay 5DK, thereby deenergizing that relay which, in turn, closes its contact members 5DK1, 5DK3 and 5DK2 to restore the circuits of the stop signal lamp 5DT in car A, the stop signal lamp B5DT in car B and the registering relay 5DR for the fifth floor to their normal condition.

It is now assumed that the car attendant in car A opens the door to permit the loading and unloading of passengers and then presses the

"down" push button DP to prepare the car for a down trip.

The closing of the contact members DP1 of the down direction push button DP prepares a circuit for energizing the down direction switch D, which circuit will be completed when the doors are closed.

The pressing of the down push button DP opens its contact members DP2, thereby deenergizing the up direction preference relay W, which, in turn, closes its contact members W1, thereby completing a circuit for energizing the down direction preference relay X to prepare the circuits of car A for the down trip. This circuit extends from the supply conductor L+1 through the closed contact members UP2 of push button UP, the coil X and the contact members W1 to the supply conductor L-1.

Inasmuch as the up direction preference relay W has been deenergized to open its contact members W3 and the down direction preference relay X has been energized to close its contact members X3, the holding coils 1CC, 2CC, 3CC, 4CC and 5CC for the car buttons in car A have been deenergized to release all the push buttons operated on the up trip and have been reenergized so that on the down trip as the push button is pressed inwardly, it will be held in that position by the corresponding holding coil until the car gets to the end of its down trip.

The coil of the electromagnet 41 which is in parallel relation to the coil of the relay X is also energized by the closing of the contact members W1 of relay W to tilt the floor selector arm SM from its "up trip" position to its "down trip" position, thereby preparing the floor selector for the down trip.

With the floor selector arm SM in the down position, the brush 36 engages the contact segment 5g and thereby completes a circuit for maintaining the floor lantern 5DL at the fifth floor in a lighted condition while the car stands at that floor. This circuit extends from the supply conductor L+2 (Fig. 3) through the down lamp 5DL, contact segment 5g, brush 36 and the contact members H2 to the supply conductor L-2.

Also the down contact brush 37 engages the down zone feeding contact 5h, thereby energizing the down zone feed relay 5DY by a circuit extending from the supply conductor L+2 through the coil 5DY, the contact segment 5H and brush 37 to the supply conductor L-2.

The closing of the contact members 5DY1 feeds the zone circuit represented by conductor 44 leading to the down lamps 4DT, etc., and the annunciator in car A; that is, these contact members connect one portion of the zone circuit 44 to the supply conductor L-2, thus preparing that zone circuit for operation. Inasmuch as the down call at the fourth floor is registered and is awaiting the approach of a down car, the closing of the contact members 5DY1 feeding the down zone circuit for car A causes the down signal lamp 4DT in car A to be lighted by a circuit extending from the supply conductor L+2 to the lamp 4DT and the contact members 4DR1, 4DK1 and 5DY1 to the supply conductor L-2. The lighting of the lamp 4DT notifies the attendant in car A that a waiting passenger at the fourth floor desires him to make a down stop at that floor.

It should be observed at this point that the circuit which was prepared for the lamp 4DT by the closing of the contact members 4DR1 on the registering relay 4DR could not be completed through any other portion of the zone circuit 44

because the zone relay contact members 4DZ1 were open in conductor 44 as a result of car B standing at the third floor on a down trip.

The energization of the zone feeding relay 5DY also closes its contact members 5DY2, thereby feeding the zone circuit represented by the conductor 45 leading to the response signalling relays M, O, P and Q for car A.

It will be assumed that the operator upon noticing the lighting of the stop signal lamp 4DT 10 indicating a down stop at the fourth floor, thereupon presses the push button 4C in the car to notify the passenger that his call has been accepted, and which car will make the stop for him and also to stop the car when it arrives at the 15 fourth floor.

The pressing of the car stop button 4C energizes the stopping contact segment 4e and also completes a circuit for energizing the response signalling relay N, which circuit extends from the 20 supply conductor L+1 (Fig. 3) through the contact members of push button 4C, the coil of response signalling relay N, conductor 54, contact members X4, 4DR2 and 5DY2 to the supply conductor L-1.

The energization of the response signalling relay N closes its contact members N3, thereby completing a self-holding circuit for itself and causing the coil N to remain energized until the restoring coil NC is energized to restore it to its normal 30 condition.

The closing of the contact members N2 of relay N completes a circuit for lighting the down floor lantern 4DL for car A at the fourth floor, which circuit extends from the supply conductor L+2 35 through lamp 4DL and the contact members N2 and X2 to the supply conductor L-2. Thus, it is seen that the down floor lantern at the fourth floor for car A is lighted as soon as the car attendant presses the corresponding stop car button 40 and thereby indicates to the waiting down passenger at the fourth floor that his call has been acknowledged, that a car will stop for him, and which door the car will stop at so that he may at once step to that door and be ready to board 45 the car when it arrives and the door opens.

It will be noted that in this illustration of my invention, the zones do not extend "around the corner", so to speak; that is, the up trip is divided into a number of zones and the down trip is 50 divided into a number of zones but no zone includes portions of both the up and the down trips. If desired, this system may be readily constructed to extend the zones "around the corner" as shown in the copending patent application of Edgar M. 55 Bouton and myself, filed September 9, 1933, Serial No. 688,784 and assigned to the Westinghouse Electric Elevator Company to which reference may be had for further details.

The energization of the relay N also closes its 60 contact members N4, thereby energizing the down preventing relay 4DK by a circuit extending from the supply conductor L+3 (Fig. 4) through the contact members N4, the contact members X8 and the coil 4DK to the supply conductor L-3.

The energization of the relay 4DK operates to prevent any other car from receiving the down stop signal registered for the fourth floor and accepted by car A. To do this, the energized relay 4DK opens its contact members 4DK3 (Fig. 5) 70 in the circuit leading to the down signal lamp B4DT in the annunciator of car B. Thus, it will be seen that even though car B should come to the fifth floor or pass car A, the down signal lamp for the fourth floor cannot be lighted in car B. 75

The energization of the relay **4DK** also opens its contact members **4DK1** (Fig. 3) in the circuit to the down signal lamp **4DT** in car A, thereby extinguishing that lamp.

5 The energization of the relay **4DK** opens its contact members **4DK2** in the circuit of the stop signal registering relay **4DR**, thereby deenergizing that relay and preventing its reenergization until the car stops at the fourth floor.

10 It will be assumed now that the attendant in car A closes the car door (not shown) thereby closing the door contact members **50** and thus completing a circuit for energizing the down direction switch **D** to move the car downwardly.

15 This circuit extends from the supply conductor **L+1** through the contact members **DPI** of down switch **DP**, the coil of down switch **D** and the contact members **U4**, **F1**, and **50** to the supply conductor **L-1**. The energization of the down

20 direction switch **D** closes its contact members **D1**, **D2**, **D3**, **D4** and **D6** and opens its contact members **D5**, to effect the downward movement of the car.

The closing of the contact members **D4** completes a self-holding circuit for the down switch **D**.

The opening of the contact members **D5** prevents energization of the up direction switch **U** while the car is being operated downwardly.

30 The closing of the contact members **D1** and **D2** energizes the separately excited field winding **23** and the generator **22** by a circuit extending from the supply conductor **L+1** through the contact members **D2**, the winding **23**, the contact members **D1** and resistor **R24** to the supply conductor **L-1**.

The closing of the contact members **D3** completes a circuit for energizing the brake magnet **6** to release the brake **5** and to also energize the 40 inductor restoring relay **H**.

The restoring relay **H** upon being energized closes its contact members **H1** thereby preparing the circuits of the decelerating and stopping relays **E** and **F** for energization when a stop is 45 to be made.

The opening of the contact members **H2** of the energized relay **H** extinguishes the down lamp **5DL** at the fifth floor.

Inasmuch as the field winding **23** is energized 50 and the brake **5** is released, the generator **22** supplies current to the hoisting motor **18**, which, in turn, operates the hoisting drum **13** to lower the car in the hatchway.

The energized down direction switch **D** also 55 closes its contact members **D6**, thereby energizing the high speed relay **V**, which, in turn, closes its contact members **V1** to eliminate the resistor **R24** from the circuit of the field winding **23** of the generator, thereby increasing the speed of 60 the car.

The car now moves downwardly and in so doing causes the floor selector arm **SM** to move downwardly on the floor selector, thereby bringing the down stopping brush **34** into engagement 65 with the energized down stopping contact segment **4e**, thereby completing a circuit for energizing the stopping relay **S** to stop the car at the fourth floor, which circuit extends from the supply conductor **L+1** through the contact members 70 of the car button **4C** the contact segment **4e**, brush **34** and the coil of stopping relay **S** to the supply conductor **L-1**.

The energized stopping relay **S** closes its contact members **S1**, thereby completing a circuit 75 for energizing the decelerating relay **E** to de-

celerate the car as it moves closer to the fourth floor. The circuit for this relay extends from the supply conductor **L+1** through the coil **E** and the contact members **S1** and **H1** to the supply conductor **L-1**.

The inductor maintaining relay **G** is also energized as heretofore described, thus closing its contact members **G1** to provide a self-holding circuit for the inductor relays.

As car A approaches closer to the down stop 10 at the fourth floor, the energized inductor relay **E** passes the down high speed inductor plate **DE** for the fourth floor, thereby opening its contact members **E2** and thus deenergizing the high speed relay **V**, which, in turn, opens its contact members **V1** and thereby reinserts the resistor **R24** in the circuit of the generator field winding **23** to decelerate the car from its high speed to its stopping speed.

The deenergization of the high speed relay **V** 20 also closes its contact members **V2**, thereby energizing the stopping inductor relay **F**, which may now be operated to bring the car to a stop.

At this time the brush **34** runs off the stopping contact segment **4e** (Fig. 2) and thereby deenergizes the stopping relay **S** and restores it to its normal condition.

As car A approaches still more closely to the fourth floor, at its stopping speed, the stopping inductor relay **F** comes opposite the down inductor plate **DF** for the third floor and is thereby operated to open its contact members **F2**, thus deenergizing the down direction switch **D**.

The deenergization of the down direction **D** opens its contact members **D1** and **D2** to deenergize the generator field winding **23**; and opens its contact members **D3** to deenergize the brake magnet **6** and the inductor restoring relay **H**.

The deenergization of the field winding **23** and 40 the application of the brake **5** by the deenergization of the brake magnet **6** causes the car to stop level with the second floor and the deenergization of the relay **H** opens its contact members **H1** to deenergize and restore the inductor lock- 45 ing relay **G**, the decelerating inductor relay **F** and the stopping inductor relay **E** so that they will not operate to stop the car until relay **S** is again energized.

The deenergization of relay **H** also closes its 50 contact members **H3** and thereby completes a circuit for energizing the restoring coil **NC** on the relay **N** to return that relay to its normal condition. This circuit extends from the supply conductor **L+1** through the contact members 55 **H3**, brush **35**, contact segment **4f**, the coil **NC**, conductor **54**, contact members **N3** and conductors **52** and **53** to the supply conductor **L-1**.

The deenergization of the response signalling relay **N** opens its contact members **N4**, thereby 60 deenergizing the preventing relay **4DK** and returning it to its normal condition. The deenergized relay **4DK** closes its contact members **4DK1** to restore the circuit of the stop signal lamp **4DT** in car A, and closes its contact members **4DK3** (Fig. 5) to restore the circuit for the stop signal lamp **B4DT** in car B. The restored stop signal lamps are again ready for operation in their proper order under normal conditions. The 70 energization of relay **4DK** also closes its contact members **4DK2** to restore the registering relay **4DR** to its normal condition.

Inasmuch as car A is now stopped at the fourth floor on a down trip, the car attendant may open 75

the door for the waiting passenger to enter the car.

Referring back to the point in the operation of car A where it left the ground floor, it will be recalled that the zone feeding relay **1UY** was energized by the position of the brush **33** on contact segment **1d**. As car A moves up to the second floor, the contact brush **33** moves out of engagement with segment **1d** and into engagement with the contact segment **2d** thus deenergizing zone feeding relay **1UY** and energizing zone feeding relay **2UY**.

The deenergization of the zone feeding relay **1UY** opened its contact members **1UY1** leading to the up zone conductor **43** for car A in connection with the up stop signal lights in car A, and the opening of the contact members **1UY2** opened the feed circuit to the zone circuit **46**. The energization of the zone feeding relay **2UY** closed its contact members **2UY1** leading to that section of the zone circuit **42** above the contact members **2UZ1** of the zone relay **2UZ**. The closing of the contact members **2UY3** (Fig. 4) closed the circuit to the zone relay **2UZ**, which energized that relay and caused it to open its contact members **2UZ1**.

Therefore, with car A at the second floor and with the contact members **2UZ1** open and the contact members **2UY1** closed, no stop signal calls for floors above the second floor could be received by car A but calls below the second floor could not be received by car A. With car A standing at the second floor, the effective zone for receiving stop signal calls by car A extended in front of that car up to the uppermost terminal because no car was stationed above car A. Thus the zone above car A may be called the effective zone and the zone below car A may be called the ineffective zone.

On the other hand, the effective signal zone for car B standing on a down trip at the third floor extended down to and included the first floor but could not extend to car A at the second floor, because the floor selector arm **BSM** of car B was in a down position and not in an up position.

It should also be noted that the deenergized condition of zone feeding relay **1UY** opens its contact members **1UY2** in the zone circuit **46** leading to the response signalling relays and that the energized condition of zone feeding relay **2DY** has energized the zone relay **2UZ** which opens its contact members **2UZ2** in the zone circuit **46**, thereby cutting off the response signalling relays for car A below the third floor.

As car A moved from the second floor to the third floor, the zone feeding relay **2UY** was deenergized and the feeding relay **2UY** was energized by the zone feeding brush **33** moving from the contact segment **2d** to the contact segment **3d**. In this position of car A, its signal zone now extends from car A at the third floor up to and including the upper terminal. Similarly, as the car advances to the fourth and fifth floor, the signal zone for car A advances with it and the signal circuit below it is cut off by the operation of the zone feeding relays **UY** and the zone relays **UZ**.

Returning now to a consideration of car B standing at the third floor on a down trip, it will be assumed that a waiting passenger at the lower terminal, desirous of making an up trip, presses the up floor button **1UJ** to give a stop signal in the nearest approaching car.

The operation of the button **1UJ** closes its contact members and, thereby energizes the registering relay **1UR** by a circuit extending from the supply conductor **L+3** through the contact mem-

bers of button **1UJ**, the coil **1UR**, and the contact members **1UK2** to the supply conductor **L-3**.

The energization of the registering relay **1UR** closes its contact members **1UR3** and thereby provides a self-holding circuit for itself.

The energization of relay **1UR** closes its contact members **1UR1** in the circuit leading to the stop signal lamp **1UT** in car A at the fourth floor but that stop signal fails to light because the zone contact members **3DZ1** and the zone feeding relay contact members **3DY1** and **2DY1** are open, by reason of the position of car A at the fourth floor, and, therefore, no current can feed to the stop signal lamp **1UT**. Thus the signal lamp **1UT** in car A for the lower terminal does not light and it is the zone system that prevents it from lighting because car B at the third floor is the nearest approaching car to the registered stop signal at floor 1.

The energization of the relay **1UR** also closes its contact members **1UR2** in the circuit leading to the response signalling relay **Q** of car A but no circuit can be completed through relay **Q** by reason of the fact that the zone relay contact members **3DZ2** are open and the zone feeding relay contact members **3DY2** and **2DY2** are open, thus preventing any current from flowing through the relay **Q** even if the button **1C** in car A were operated.

It may be noted here that as a result of this system if any other car than the nearest approaching car to a stop signal operates a car button to stop at the same floor as the stop signal, the operated car button will not be able to energize its response signalling relay for the stop signal floor and, therefore, will not be able to light its corresponding lantern as it approaches that floor. However, its floor lantern will light when it comes to rest at the floor.

In view of the above, it is seen that the stop signal registered at floor 1 cannot get through to car A which is behind car B on account of the signal zone system.

Referring again to the energization of relay **1UR**, this condition causes it to close its contact members **1UR5** in the circuit leading to the response signalling relay **BQ** and inasmuch as the contact members **2DZ4** and **B3DY3** are closed by reason of the position of car A, the response signalling relay **BQ** for car B can be energized by operation of the push button **B1C** in car B.

The energized relay **1UR** closes its contact members **1UR4** in the circuit leading to the stop signal lamp **B1UT** in car B and thereby energizes and lights that lamp through a circuit extending from the supply conductor **L+5**, the lamp **B1UT**, contact members **1UR4** and **1UK3**, the contact members **2DZ3** and conductor **59** and contact members **B3DY2** to the supply conductor **L-6**.

The lighting of the stop signal lamp **B1UT** in car B notifies the attendant in that car that a passenger wants a car at floor 1. Thereupon the car attendant in car B at once presses his car button **B1C** to acknowledge the receipt of the stop signal to take over the stop call for that floor, to light the lantern for car B at that floor to indicate to the waiting passenger which door he should go to in order to board the car when it arrives, and also to stop the car when it arrives at floor 1.

The pressing of the button **B1C** energizes the stopping contact segment **B1e** and also the response signalling relay **BQ** by a circuit extending from the supply conductor **L+5** (Fig. 5) through

the contact members of button B1C, the coil BQ, the contact members BX11, 1UR5 and B2DY3 to the supply conductor L-5.

The energization of the relay BQ closes its contact members BQ4 to provide a self holding circuit for itself, which circuit extends from the coil BQ through the contact members BQ4 and conductors 60 and 61 to the supply conductor L-5.

10 The energization of the relay BQ closes its contact members BQ2, thereby lighting the signal lamp B1UL for car B at floor 1 by a circuit extending from the supply conductor L+6 through lamp B1UL, the contact members BQ2 and the contact members BW6 to the supply conductor L-6.

15 The lighting of the lamp B1UL notifies the waiting passenger at the first floor that car B will answer his stop signal and he may at once 20 step to the door of car B and be ready to board that car as soon as it arrives at the first floor.

25 The energized relay BQ also closes its contact members BQ1, thereby energizing the preventing relay 1UK by a circuit extending from the supply conductor L-3 (Fig. 4) through the contact members BQ1 and BX4 and the coil 1UK to the supply conductor L-3.

30 The energization of the preventing relay 1UK opens its contact members 1UK1 (Fig. 3) in the circuit leading to the stop signal lamp 1UT in car A and thereby prevents any stop signal to that car from the operation of the push button at the first floor. The energization of relay 1UK also opens its contact members 1UK2 (Fig. 4) in 35 the circuit of the registering relay 1UR, thereby deenergizing that relay and preventing its re-energization until the registered stop call at the first floor is answered by a car.

35 The energization of the relay 1UK also opens 40 its contact members 1UK3 (Fig. 5) in the circuit leading to the lighted stop signal lamp B1UT in car B, thereby extinguishing that lamp and preventing its relighting until after the call is answered.

45 Car B is still standing with its door open on a down trip at the third floor.

It will be assumed now that for some reason, the attendant on car A closes his door and presses the down push button DP and thereupon causes 50 car A to start downwardly, as previously described in moving car A from the upper terminal to the fourth floor.

55 As car A moves toward the first floor, the attendant presses the car button 1C in car A to make the car stop at the first floor. The pressing of button 1C closes its contact terminals and the holding coil 1CC keeps them closed until car A reaches the lower floor.

60 The closing of the contact members of car button 1C energizes the stopping contact segment 1e of car A for the lower floor.

65 As car A approaches the lower floor, its stopping brush 34 engages the stopping contact segment 1e and thereby energizes the stopping relay S. The energization of the stopping relay S energizes the inductor relays F and E, which causes car A to be decelerated and stopped at the first floor by the inductor relays cooperating with the inductor plates as heretofore described. Under 70 this condition of operation, it will be seen that the acknowledgement of the stop signal for floor 1 by the attendant of car B rendered that call ineffective to signal car A when it subsequently became the nearest car to the first floor by passing car B. Car A failed to pick up the stop sig-

nal for the first floor after it passed car B because of the open contact members 1UK1 in the circuit to the stop signal lamp 1UT in car A. Also, the car attendant in car A could not light the floor lantern for car A at the first floor by 5 operating the switch button 1C in his car, because he could not energize the response signalling relay by reason of the open condition of the contact members 1UR2 in the circuit to relay Q caused by the deenergized condition of the relay 10 1UR.

In the present case, it will be assumed now that the attendant on car A does not open the door at the lower floor but operates the up direction push button UP as formerly described and 15 thereby causes the car to move upwardly and finally parks it at, say, the fourth floor.

It will also be assumed now that the attendant on car B at the third floor closes his door and operates the down direction push button BDP 20 to move the car downwardly in answer to the stop signal on the first floor. The operation of the down button BDP closes its contact members DP1 thereby energizing the down direction switch BD for car B by a circuit extending from the supply conductor L+5 (Fig. 5) through the contact members BDP1, the coil BD, and the contact members BU4, BF2 and B50 to the supply conductor L-5. The energization of the down switch BD closes its contact members BD1, BD2, 30 BD3, BD4 and BD6 and opens its contact members BD5.

The closing of the contact members BD4 completes a self holding circuit around the contact members BDP1 of button BDP for the coil of the 35 down direction switch BD thereby maintaining that switch in an energized condition until the stopping inductor relay BF opens its contact members BF2.

The closing of contact members BD1 and BD2 40 energizes the separately excited field winding B23 of the generator B22 by a circuit extending from the supply conductor L+5 through the contact members BD2, the winding B23, the contact members BD1 and the resistor BR24 to the supply conductor L-5.

The closing of the contact members BD3 completes a circuit for energizing the brake magnet B6 to release the brake B5 by a circuit extending from the supply conductor L+5 through the contact members BD3 and the coil B6 to the supply conductor L-5. The closing of the contact members BD3 also completes a circuit for energizing the restoring relay BH which is in parallel 50 with the brake magnet B6. 55

The restoring relay BH, upon being reenergized, closes its contact members BH1, thereby preparing the circuits of the accelerating and stopping inductor relays BE and BF for energization when a stop is to be made. 60

The opening of the contact members BH2 on relay DH extinguishes the down lamp B3D1 at the third floor.

The opening of the contact members BD5 interlocks the circuit for the up direction switch BU 65 and prevents energization of that switch while car B is being operated downwardly.

Inasmuch as the field winding B23 is energized and the brake B5 is released by the energization of the brake magnet B6, the generator B22 70 supplies current to the hoisting motor B18 which, in turn, operates the hoisting drum B13 to lower the car B in the hatchway.

The closing of the contact members BD6 energizes the high speed relay BV by a circuit ex- 75

tending from the supply conductor L+5 through the contact members BD6 and BE2 and the coil BV to the supply conductor L-5.

The energization of the high speed relay BV 5 closes its contact members BV1 to eliminate the resistor BR24 from the circuit of the field winding B23, thereby causing the variable voltage system to move the car downward at high speed.

As car B approaches the first floor, its stop 10 brushes B34 engages the energized stopping contact segment B1e and thereby energizes the stopping relay BS for car B by way of a circuit extending from the supply conductor L+5 through the contact members of button B1C, the contact 15 segment B1e, the brush B34 and the coil BS to the supply conductor L-5.

The energized stopping relay BS closes its contact members BS1 thereby energizing the decelerating and inductor relay BE and the inductor 20 maintaining relay BG. The circuit for the relay BE extends from the supply conductor L+5 through the coil BE, the contact member BS1, and the contact members BH1 to the supply conductor L-5. The energization of the maintaining 25 relay BG which is in parallel with the coil BE closes its contact members BG1 and thereby keeps the inductor relay circuit closed until the car makes the stop.

As the car B approaches closer to the lower 30 floor, the energized inductor relay BE passes the down high speed inductor plate BDE for the first floor and is thereby caused to open its contact members BE2, thus deenergizing the high speed relay BV which, in turn, opens its contact members 35 BV1 and thereby reinserts the resistor BR24 in the circuit of the generator field winding B23 to decelerate the car B from its high speed to its stopping speed.

The deenergization of the high speed relay BV 40 also closes its contact members BV2, thereby energizing the stopping inductor relay BF.

At approximately this time, the brush B34 runs off the contact segment B1e thereby deenergizing the stopping relay BS and restoring it to its 45 normal condition.

As car B approaches still more closely to the first floor at its stopping speed, the stopping inductor relay BF comes opposite the inductor plate BDF for the first floor and is thereby operated to open its contact members BF2, thus deenergizing the down direction switch BD.

The deenergization of the switch BD opens its contact members BD1 and BD2 to deenergize the generator field B23 and opens its contact members BD3 to deenergize the brake magnet B6 and the inductor restoring relay BH.

The deenergization of the field winding B23 and the application of the brake B5 by the deenergization of the brake magnet B6 causes the car 60 B to stop level with the first floor; and the deenergization of the relay BH opens its contact members BH1 to deenergize and restore the inductor locking relay BG, the accelerating inductor relay BF and the stopping inductor relay BE 65 so that they will not be effective to stop the car in its future operation until the stopping relay BS is again energized to effect the stopping of the car.

The deenergization of the relay BH also closes 70 its contact members BH3 and thereby completes a circuit for energizing the restoring coil BQC on the relay BQ to return that relay to its normal condition. This circuit extends from the supply conductor L+5 through the contact members 75 BH3, brush B35, contact segment B1f, coil BQC,

the contact members BQ3, and the conductors 60 and 61 to the supply conductor L-5.

The deenergization of the response signalling relay BQ opens its contact members BQ1 thereby deenergizing the preventing relay UK and returning it to its normal condition in which condition the relay UK1 (Fig. 3) in the circuit of the stop signal lamp UT in car A; closes its contact members UK2 (Fig. 4) in the circuit of the registering 10 relay UR to restore the circuit of that relay to its normal condition; and closes its contact members UK3 (Fig. 5) in the circuit of the stop signal lamp B1UT in car B. The restored stop signal lamps are again ready for operation in 15 their proper order under normal conditions.

Car B is now stopped at the ground floor and the car attendant may open the door and let the waiting passenger enter and then reclose the door. It will be assumed that the car attendant then operates the car push button BUP to start the car upwardly and, in turn, stops car B at the second floor.

It should be noted that although car A could not light its floor lantern at floor 1 through the operation of its car button 1C, yet its floor lantern 25 1UL is lighted when the car comes to rest at the floor because its down lantern brush 33 is in engagement with its floor lantern contact segment 30 1g and its inductor restoring relay H is deenergized and closes its contact members H2 (Fig. 3).

By the above it is seen that when a car accepts a stop signal call registered at a floor, its floor lantern at that floor is lighted immediately and stays lighted until the car comes to the floor. If, in the meantime, another car passes that car and reaches the signalling floor first, the passing car does not pick up the stop signal accepted by the passed car, neither does it light its floor lantern until it actually comes to rest at the signalling 40 floor.

Although I have illustrated and described only one specific embodiment of my invention, I desire it to be understood that many changes therein and modifications thereof may be made without departing from the spirit and scope of the invention.

I claim as my invention:

1. In an elevator system for operating a plurality of cars past a floor, a signal device in each car, a switch at the floor and means responsive to operation of the switch and to the position of the cars for operating the signal device in only the nearest approaching car for the 50 direction of the switch regardless of the distance of said only car from said switch when the cars are operating in their normal spaced apart relation.

2. In an elevator system for operating a plurality of cars past a floor, a signal device in each car, a switch at the floor, and means responsive to operation of the switch and to the position of the cars for operating the signal device in the nearest approaching car for the direction of the 55 switch regardless of its distance from the switch and for preventing the operation of the signal devices in the other cars when the cars are operating in their normal spaced apart relation.

3. In an elevator system for operating a plurality of cars past a plurality of floors, a signal device in each car for each floor, a switch at each floor, means responsive to operation of a switch at a floor and to the position of the cars for operating the signal device for that floor in the near- 75

est approaching car for the direction of that switch at that floor and for preventing the operation of the switch from operating the signal devices in the other cars when the cars are operating in their normal spaced apart relation.

5. In an elevator system for operating a plurality of cars past a plurality of floors, a plurality of switches, one for the up direction and one for the down direction at each floor, a plurality of signal devices, one for each direction for each floor in each car, means responsive to operation of a switch at a floor and the position of the cars for operating the signal device corresponding to that switch in the nearest approaching car for that switch and for preventing the operation of the corresponding signal devices in the other cars when the cars are operating in approximately their normal spaced apart relation.

6. In an elevator system for operating a plurality of cars past a plurality of floors, a plurality of switches, one for the up direction and one for the down direction at each floor, a plurality of devices responsive to operation of the switches for registering stop signal calls, one registering device for each switch, a plurality of signal devices, one for each direction for each floor in each car, means responsive to the operation of a registering device and to the position of the cars for operating the signal device for the corresponding direction and floor in only the nearest approaching car for that direction at that floor when the cars are operating in their normal spaced apart relation.

7. In an elevator system for operating a plurality of cars past a plurality of floors, a plurality of switches, one for the up direction and one for the down direction at each floor, a plurality of devices responsive to operation of the switches for registering stop signal calls, one registering device for each switch, a plurality of signal devices in the cars, one for each direction for each floor in each car, a plurality of zone relays common to all the cars for defining signal zones therefor, means responsive to the position of the cars for operating the zone relays in accordance with the position of the cars, means responsive to the operation of the zone relays and to the operation of a call registering device for a floor for operating the signal device corresponding to the operated call registering device in only the nearest approaching car, when the cars are operating in their normal spaced apart relation.

8. In an elevator system for operating a plurality of cars past a plurality of floors, a plurality of switches one for the up direction and one for the down direction at each floor, a plurality of devices responsive to operation of the

switches for registering stop signal calls, one registering device for each switch, a plurality of signal devices in the cars, one for each direction for each floor in each car, a plurality of zone relays common to all the cars for defining signal zones therefor, means responsive to the position of the cars for operating the zone relays in accordance with the position of the cars, means responsive to the operation of the zone relays and to the operation of a call registering device for a floor for operating the signal device corresponding to the operated call registering device in the nearest approaching car, and for preventing the operation of the corresponding signal devices in the other cars, when the cars are operating in their normal spaced apart relation.

9. In an elevator system for operating a plurality of cars past a plurality of floors, a plurality of switches, one for the up direction and one for the down direction at each floor, a plurality of devices responsive to operation of the switches for registering stop signal calls, one call registering device for each switch, a plurality of signal devices in the cars, one for each direction for each floor in each car, a plurality of zone relays common to the cars for defining signal zones therefor, a plurality of zone feeding relays for each car for operating the zone relays, means for operating the zone feeding relays in accordance with the positions of the cars, and means responsive to the operation of a call registering device for a floor and to the operation of the zone feeding relays and the zone relays for operating the signal devices corresponding to the operated call registering device in the nearest approaching car, when the cars are operating in their normal spaced apart relation.

10. In an elevator system for operating a plurality of cars past a plurality of floors, a plurality of switches, one for the up direction and one for the down direction at each floor, a plurality of devices responsive to operation of the switches for registering stop signal calls, one call registering device for each switch, a plurality of signal devices in the cars, one for each direction for each floor in each car, a plurality of zone relays common to the cars for defining signal zones therefor, a plurality of zone feeding relays for each car for operating the zone relays, means for operating the zone feeding relays in accordance with the positions of the cars, and means responsive to the operation of a call registering device for a floor and to the operation of the zone feeding relays and the zone relays for operating the signal device corresponding to the operated call registering device in only the nearest approaching car, when the cars are operating in their normal spaced apart relation.

11. In an elevator system for operating a plurality of cars past a plurality of floors, a plurality of switches, one for the up direction and one for the down direction at each floor, a plurality of devices responsive to operation of the switches for registering stop signal calls, one call registering device for each switch, a plurality of signal devices in the cars, one for each direction for each floor in each car, a plurality of zone relays common to the cars for defining signal zones therefor, a plurality of zone feeding relays for each car for operating the zone relays, means for operating the zone feeding relays in accordance with the position of the cars, and means responsive to the operation of a call registering device for a floor and to the operation of the zone feeding relays and the zone relays for operating the

signal device corresponding to the operated call registering device in the nearest approaching car and for preventing the operation of the corresponding signal devices in the other cars, when 5 the cars are operating in their normal spaced apart relation.

12. In an elevator system for operating a plurality of cars past a floor, an indicating signal device at the floor for each car, a control means 10 in each car for the floor, an annunciator signal device in each car for the floor, a switch at the floor, means responsive to operation of the switch and to the position of the cars for operating the annunciator signal device in only the nearest 15 approaching car, when the cars are operating in their normal spaced apart relation, and means responsive to operation of the switch and to the position of the cars and to operation of the control device in said nearest approaching car for 20 the corresponding floor for operating the indicating signal device at that floor for that car.

13. In an elevator system for operating a plurality of cars past a plurality of floors, an indicating signal device at each floor for each car, a control device for each floor in each car, an annunciator signal device for each floor in each car, a switch at each floor, means responsive to operation of a switch at any floor and to the position of the cars for operating the annunciator 30 signal device corresponding to the operated switch in only the nearest approaching car, when the cars are operating in their normal spaced apart relation, and means responsive to the operated switch and to the position of the cars and to 35 operation of the control device in said nearest approaching car for operating the indicating device for that car at the floor of the operated switch to indicate to the actuator of the switch that a car will stop in response thereto and which 40 car will make the stop.

14. In an elevator system for operating a plurality of cars past a plurality of floors, an indicating signal device at each floor for each car, a control device for each floor in each car, an 45 annunciator signal device for each floor in each car, a switch at each floor, means responsive to operation of a switch at any floor and to the position of the cars for operating the annunciator signal device corresponding to the operated switch in only the nearest approaching car, when the 50 cars are operating in their normal spaced apart relation, and means responsive to the operated switch and to the position of the cars and to operation of the control device in said nearest approaching car for operating the indicating device for that car at the floor of the operated switch to indicate to the operator of the switch that a car will stop in response thereto and which car 55 will make the stop and for stopping the car when it arrives at that floor.

15. In an elevator system for operating a plurality of cars past a plurality of floors, an indicating signal device at each floor for each car, a control device for each floor in each car, an annunciator signal device for each floor in each car, a switch at each floor, means responsive to operation of a switch at any floor and to the position of the cars for operating the annunciator signal device corresponding to the operated switch in only the nearest approaching car, when the cars 65 are operating in their normal spaced apart relation, and means responsive to the operated switch and to the position of the cars and to operation of the control device in said nearest approaching car for operating the indicating device for that 70 car.

car at the floor of the operated switch to indicate to the operator of the switch that a car will stop in response thereto and which car will make the stop and for preventing operation of the corresponding annunciator signal devices in the other 5 cars.

16. In an elevator system for operating a plurality of cars past a plurality of floors, an indicating signal device at each floor for each car, a control device for each floor in each car, an annunciator signal device for each floor in each car, a switch at each floor, means responsive to operation of a switch at any floor and to the position of the cars for operating the annunciator signal device corresponding to the operated switch in only the nearest approaching car, when the cars are operating in their normal spaced apart relation and means responsive to the operated switch and to the position of the cars and to operation of the control device in said nearest approaching car for operating the indicating device for that car at the floor of the operated switch to indicate to the operator of the switch that a car will stop in response thereto and which car will make the stop and for preventing the operation of the corresponding control device in any other car from operating its indicating signal device at the floor of the operated button until said other car stops thereat.

17. In an elevator system for operating a plurality of cars past a plurality of floors, an indicating signal device at each floor for each car, a control device for each floor in each car, and an annunciator signal device for each floor in each car, a switch at each floor, means responsive to operation of a switch at any floor and to the position of the cars for operating the annunciator signal device corresponding to the operated switch in only the nearest approaching car, when the cars are operating in their normal spaced apart relation, and means responsive to the operated switch and to the position of the cars and to operation of the control device in said nearest approaching car for operating the indicating device for that car at the floor of the operated switch to indicate to the actuator of the switch that a car will stop in response thereto and which car will make the stop and for cancelling the operated annunciator signal device and keeping it in ineffective condition until the car answers the 50 stop.

18. In an elevator system for operating a plurality of cars past a plurality of floors, an indicating signal device at each floor for each car, a control device for each floor in each car, an annunciator signal device for each floor in each car, a switch at each floor, a plurality of devices responsive to operation of the switches for registering stop signal calls, one registering device for each switch, when the cars are operating in 60 their normal spaced apart relation, means responsive to an operated registering device and to the position of the cars for operating the annunciator signal device for the corresponding floor in only the nearest approaching car, and means responsive to said operated registering device and to the position of the cars and to operation of the corresponding control device in said nearest approaching car for operating the indicating signal device of that car at the floor corresponding to the registering device.

19. In an elevator system for operating a plurality of cars past a plurality of floors, an indicating signal device at each floor for each car, a control device for each floor in each car, an an- 75

nunciator signal device for each floor in each car, a switch at each floor, a plurality of devices responsive to operation of the switches for registering stop signal calls, one registering device for each switch, means responsive to an operated registering device and to the position of the cars for operating the annunciator signal device for the corresponding floor in only the nearest approaching car, when the cars are operating in their normal spaced apart relation, and means responsive to said operated registering device and to the position of the cars and to operation of the corresponding control device in said nearest approaching car for operating the indicating signal device of that car at the floor corresponding to the registering device, and for restoring the operated registering device and preventing its further operation until the car answers the call.

20. In an elevator system for operating a plurality of cars past a plurality of floors, a plurality of switches, one for the up direction and one for the down direction at each floor, a plurality of signal devices, one for each direction for each floor in each car, means responsive to operation of a switch at a floor by an intending passenger and to the position of the cars for operating the signal device corresponding to that switch in the nearest approaching car when the cars are operating in their normal spaced apart relation, means responsive to the position of the cars for preventing the operation of the corresponding signal device in the other cars, a plurality of indicating devices one for each direction at each floor for each car, a plurality of control devices, one for each floor in each car, and means responsive to said operated switch and to the subsequent operation of the corresponding control device in the nearest approaching car and to the position of the cars for operating the indicating device for said nearest approaching car at the floor of the operated switch to indicate to the waiting passenger that his stop signal has been accepted and which car will stop for him.

21. In an elevator system for operating a plurality of cars past a plurality of floors, a plurality of switches, one for the up direction and one for the down direction at each floor, a plurality of signal devices, one for each direction for each floor in each car, means responsive to operation of a switch at a floor by an intending passenger and to the position of the cars for operating the signal device corresponding to that switch in the nearest approaching car when the cars are operating in their normal spaced apart relation, means responsive to the position of the cars for preventing the operation of the corresponding signal devices in the other cars, a plurality of indicating devices one for each direction at each floor for each car, a plurality of control devices, one for each floor in each car, and means responsive to said operated switch and to the subsequent operation of the corresponding control device in the nearest approaching car and to the position of the cars for operating the indicating device for said nearest approaching car at the floor of the operated switch to indicate to the waiting passenger that his stop signal has been accepted and which car will stop for him, and means responsive to said operated control device for preventing effective operation of the control devices in the other cars to operate their indicating devices corresponding to the said operated switch.

22. In an elevator system for operating a plurality of cars past a plurality of floors, an an-

nunciator signal device for each floor in each car, a switch at each floor, a plurality of devices responsive to operation of the switches for registering stop signal calls, one registering device for each switch, a plurality of zone relays common to all the cars for defining signal zones therefor, a plurality of zone feeding relays for each car for operating the zone relays, means responsive to the position of the cars for operating the zone feeding relays, an indicating device at each floor for each car, a control device for each floor in each car, and a plurality of responsive signalling relays, one for each floor for each car, said responsive signalling relays being responsive to operation of the zone relays, the zone feeding relays, a registering relay and the control device in the nearest approaching car to the floor of the operating registering relay when the cars are operating in their normal spaced apart relation for operating the indicating device for said nearest approaching car at that floor, for preventing any other car receiving or accepting the registered call and for cancelling the registered call.

23. In an elevator system for operating a plurality of cars past a plurality of floors, an annunciator signal device for each floor in each car, a switch at each floor, a plurality of devices responsive to operation of the switch for registering stop signal calls, one registering device for each switch, an indicating signal device at each floor for each car, a control device for each floor in each car, a plurality of zone relays common to the cars for defining signal zones therefor, a plurality of zone feeding relays for each car for operating the zone relays, means for operating the zone feeding relays in accordance with the position of the cars, a plurality of response signalling relays, one for each floor for each car, said response signalling relays being responsive to operation of the zone relays, the zone feeding relays, the call registering devices and the control devices in the cars for operating the indicating device at the floor of an operated switch for the nearest approaching car to the floor of the operated switch, when the cars are operating in their normal spaced apart relation, and a plurality of preventing relays responsive to operation of the response signalling relays for preventing operation of the corresponding annunciator signalling devices in the other cars.

24. In an elevator system for operating a plurality of cars past a plurality of floors, an annunciator signal device for each floor in each car, a switch at each floor, a plurality of devices responsive to operation of the switches to register stop signal calls, one registering device for each switch, an indicating signal device at each floor for each car, a control device for each floor in each car, a plurality of zone relays common to the cars for defining signal zones therefor, a plurality of zone feeding relays for operating the zone relays, means responsive to the position of the cars for operating the zone feeding relays, a plurality of response signalling relays, one for each floor for each car, said response signalling relays being responsive to operation of the registering devices and the zone feeding relays and the call registering relays and the control devices in the cars for operating the indicating device at the floor of an operated switch for the nearest approaching car for the operated switch, and a plurality of preventing relays responsive to operation of the response signalling relays for

- restoring the operated registering relay and for maintaining it inactive until the stop call registered thereon is answered.
25. In an elevator system for operating a plurality of cars past a plurality of floors, an annunciator signal device for each floor in each car, a switch at each floor, means responsive to the position of the cars for preparing the annunciator signal device corresponding to any switch in the nearest approaching car to that switch for operation by that switch and for preventing operation of the corresponding annunciator signal devices in the other cars by that switch, when the cars are operating in their normal spaced apart relation.
26. In combination, a plurality of circuits each individual to a plurality of elevators and each normally functioning as a unit; a plurality of brushes each individual to one of said elevators and movable in accordance with the movements of the associated elevator; and means operable by any one of said brushes to divide each of the circuits into two parts and to render operable only one part said part being one of the parts associated with the elevator corresponding to said one brush.
27. In combination, a plurality of circuits each individual to a plurality of elevators and each normally functioning as a unit; a plurality of means each associated with one of said elevators and movable in accordance with movements of said elevator and each comprising only one moving brush; and means operably responsive to any one of said first mentioned means for dividing each of said circuits into two parts and for rendering operable only one part, said part being one of the parts associated with the elevator corresponding to said one of said first mentioned means.
28. In an elevator system for operating a plurality of cars past a plurality of floors, a plurality of circuits, one for each car, a plurality of zone relays common to all the cars for dividing said circuits into a plurality of effective circuit zones corresponding to the number of cars, and means for operating said zone relays and for feeding the effective circuit zones formed thereby including only one row of contact segments and a contact brush therefor for each circuit and means responsive to the operation of the cars for causing the brushes and contact segments to engage in accordance with the position of the cars.
29. In an elevator system for operating a plurality of cars past a plurality of floors, a plurality of circuits, one for the "up" direction and one for the "down" direction for each car, a plurality of "up" zone relays and "down" zone relays common to all the cars for dividing the "up" circuits and the "down" circuits into a plurality of effective and ineffective circuit zones, the effective circuit zones corresponding to the number of cars and their direction of travel, and means responsive to the position of the cars for operating the zone relays in accordance with the direction of travel and the position of the cars and for connecting the said effective circuit zones to a source of electrical energy, said last named means including only one row of contact segments and a contact brush therefor for each direction for each car.
30. In an elevator system for operating a plurality of cars past a plurality of floors, a plurality of circuits, one for each car, a plurality of zone relays for controlling the circuits, a plurality of zone feeding relays for each car for operating said zone relays to divide said circuits into a plurality of effective and ineffective circuit zones and for connecting each effective circuit zone to a source of electrical energy, and means operably responsive to the position of the cars for operating the zone feeding relays in accordance with the position of the cars.
31. In an elevator system for operating a plurality of cars past a plurality of floors, a plurality of circuits, one for each car, a plurality of zone relays for dividing each of said circuits into a plurality of sections, a plurality of zone feeding relays for operating said zone relays to connect and disconnect the sections in such manner as to provide a plurality of effective circuit zones in said circuits corresponding to the number of cars and for connecting said effective circuit zones to a source of electrical energy, and means for connecting said zone feeding relays to a source of electrical energy in accordance with the movements of the cars, said connecting means comprising only one strip of contact segments and a contact brush therefor for each car.
32. In an elevator system for operating a plurality of cars past a plurality of floors, a plurality of circuits, one for the "up" direction and one for the "down" direction for each car, a plurality of "up" zone relays and "down" zone relays common to all the cars for controlling the circuits, a plurality of contact members disposed in the circuits for operation by the zone relays, a plurality of "up" zone feeding relays and "down" zone feeding relays for each car for operating the zone relays to divide the "up" circuits into a plurality of effective circuit zones corresponding to the number of "up" cars and to divide the "down" circuits into a plurality of effective circuit zones corresponding to the number of "down" cars, and means responsive to the operation of the cars for operating the zone feeding relays in accordance with the direction of travel and position of the cars and for connecting the said effective circuit zones to a source of electrical energy.
33. In an elevator system for operating a plurality of cars past a plurality of floors, a plurality of circuits, one for the "up" direction and one for the "down" direction for each car, a plurality of "up" zone relays and "down" zone relays common to all the cars for controlling the circuits, a plurality of contact members disposed in the circuits for operation by the zone relays, a plurality of "up" zone feeding relays and "down" zone feeding relays for each car for operating the zone relays to divide the "up" circuits into a plurality of effective circuit zones corresponding to the number of "up" cars and to divide the "down" circuits into a plurality of effective circuit zones corresponding to the number of "down" cars, and means responsive to the operation of the cars for operating the zone feeding relays in accordance with the direction of travel and position of the cars and for connecting the said effective circuit zones to a source of electrical energy, said zone feeding relay operating means comprising only one row of contact segments and a contact brush therefor for each direction for each car.
34. In an elevator system for operating a plurality of cars past a plurality of floors, a plurality of switches, one for the up direction and one for the down direction at each floor, a plurality of signal devices, one for each direction for each floor in each car, and means responsive to operation of a switch at a floor and the position of the cars for operating the signal device corre- 75

sponding to that switch in the nearest approaching car for that switch when the cars are operating in their normal spaced apart relation and for operating the signal devices corresponding to that switch in the nearest approaching cars for that switch in approximately side-by-side rela-

tion when the cars are not operating in normal spaced apart relation and for preventing the operation of the corresponding signal devices in the other cars.

WILLIAM F. EAMES. 5
